DESIGN FOR A COMBINED LETTER OPENER AND TELEPHONE DIALER

Abraham Broffman, Brooklyn, N. Y.

Application April 23, 1940, Serial No. 91,891

Term of patent 3½ years

To all whom it may concern:

Be it known that I, Abraham Broffman, a citizen of the United States, residing in Brooklyn, county of Kings, and State of New York, have invented a new, original, and ornamental Design for a Combined Letter Opener and Telephone Dialer, of which the following is a specification, reference being had to the accompanying drawing, forming part thereof.

opener and telephone dialer, showing my new design.

I claim:

The ornamental design for a combined letter opener and telephone dialer, substantially as shown.

ABRAHAM BROFFMAN.
